UNITED STATES PATENT OFFICE.

PORTER W. MUNSON, OF ST. LOUIS, MISSOURI.

DESIGN FOR A ROCKER-TOY.

56,706.

Specification for Design.

Patented Nov. 30, 1920.

Application filed May 8, 1919. Serial No. 295,786. Term of patent 7 years.

To all whom it may concern:

Be it known that I, PORTER W. MUNSON, a citizen of the United States, and resident of St. Louis, State of Missouri, have invented a new, original, and ornamental Design for a Rocker-Toy, of which the following is a specification.

Reference being had to the accompanying drawing forming part thereof.

Figure 1, is a perspective view.
Fig. 2, is a bottom plan view.
Fig. 3, is a front view.
Fig. 4, is a vertical central sectional view.
I claim the ornamental design of a rocker toy, as shown.

PORTER W. MUNSON.
